UNITED STATES PATENT OFFICE.

ALFRED BOUSFIELD, OF ST. JOHNSBURY, VERMONT, ASSIGNOR TO E. AND T. FAIRBANKS AND COMPANY, OF ST. JOHNSBURY, VERMONT, A CORPORATION OF VERMONT.

WEIGHING MACHINE.

Application filed November 13, 1925. Serial No. 68,760.

My present invention relates to weighing machines, and has for its object to provide an improved knife edge pivot therefor.

In order that a scale may weigh properly, 5 the pivots in scale levers and beams must be placed with great exactness and the practice of casting the levers with the pivots in place results in the loss of many castings owing to the pivots having been improperly 10 placed or having shifted in the mould. Furthermore, the pivots lose their temper and often warp during the casting process and must be re-shaped and re-hardened, which involves grinding and heating operations that, when the pivots are fixed in the 15 lever, are difficult to carry out, especially if the lever be a heavy one. Where a pivot is thus fixed in place it must be formed of a bar of sufficient cross-section to support the 20 weight, and as these bars are of high-grade steel, their cost is considerable. The practice of inserting the pivots in holes drilled in the lever is also followed to some extent, but such inserted pivots must be formed of 25 even heavier bars than are used to form pivots which are fixed in place in casting and the cost of such inserted pivots is therefore also very great. In some types of scales it has been the custom to form the pivots 30 with a cylindrical portion that is mounted in holes drilled in the lever or other scale part, and projecting longitudinally from such cylindrical portion are the knife edges. The cylindrical portion of the pivots of this 35 character have greater area than the knife edge portion, however, in manufacturing this type of pivot, considerable difficulty has been experienced in machining the parts whereby the knife edges will be properly 40 alined.

Generally stated, a pivot falling within the scope of my invention is composed of two pieces, one of which is cylindrical in form and provided with a rectangular 45 groove, the bottom of which groove lies along the longitudinal axis of the cylinder, and the other piece is substantially rectangular in form for engaging with the sides of the groove, and has a knife edge portion resting on the bottom of the groove, the second 50 piece being frictionally retained by the first piece, and the first piece being frictionally

mounted in a hole drilled in the lever or other scale part, both pieces being fixed in position without using auxiliary fastenings. 55

The invention is illustrated in the accompanying drawings in which—

Figure 1 is an elevation of a weighing machine, showing the application of my invention thereto;

Fig. 2, is a horizontal section taken approximately on the line 2—2 of Fig. 1, most 60 of the parts being shown in plan;

Fig. 3, is a transverse section taken on the line 3—3 of Fig. 2;

Fig. 4 is a detail view of the pivot, and

Fig. 5 is a transverse section taken on the line 5—5 of Fig. 4.

My invention can be used in the various pivotal connections of weighing or other like 70 machines, therefore, I have chosen to show in the present embodiment the same applied to the scale shown in United States Letters Patent #1,346,481 issued July 13, 1920.

Referring now to the drawings, the arm 75 12 is pivotally mounted by means of a pivot 13 seated on bearings 14 carried in the top of a support 15. The forward segmental end 16 of the arm has attached thereto a tape 17, while an eccentric 18 to which is attached 80 a tape 19 is mounted so as to extend rearwardly of the pivot 13. Both of the tapes are connected to other parts of the scale mechanism and function in the manner fully described in the patent, the arm swinging 85 on its pivot during the operation of the scale in the usual well known manner.

For the purpose of facilitating construction of scale parts it has been the custom to form the arm from a casting. One end of 90 the arm is bifurcated to provide a pair of spaced hubs 20 in which are drilled alined openings 21 for receiving the pivot. The eccentric 18 is carried by the pivot in the space between the hubs 20 (see Figs. 2 and 3.) 95

As shown, the pivot comprises a cylindrical body from which projects alined knife edges that are disposed coincident with the longitudinal axis of the main body of the pivot. Heretofore pivots of this character 100 have been formed in various ways. Some have been cut from a solid piece of material, while others have been composed of assembled parts suitably fastened together. In all

cases, however, accurate machining of the parts is required so as to obtain articles suitable for use in sensitive weighing machines.

In order to produce a pivot wherein the oppositely projecting knife edges would be in perfect alinement, considerable machining and grinding has been required, which work has unreasonably increased the cost of the articles. Furthermore, it has also been difficult for the workmen to determine with accuracy whether or not the two knife edges were properly alined. Therefore, in order to obtain a better article which could be readily manufactured at little expense, the pivot 13 is composed of two pieces, a cylindrical body, which is made from a suitable length of round bar steel, and a knife edge portion 22, which is made from a suitable length of rectangular bar steel.

In producing the pivot, the cylindrical body portion has a rectangular channel or groove 23 formed the length thereof, such groove having parallel sides and a flat bottom 24, which latter is disposed coincident with the longitudinal axis of the body. The knife edge bar 22, which has a wedge-shaped portion 25 tapering from parallel sides 26, is adapted to be driven or pressed into the groove 23 with the lower edge of the portion 25 seated along the bottom 24. In forming the pivot, it is the practice to form the groove 23 of a width corresponding to the thickness of the knife edge bar 22. The

sharpened edge portion of the bar is carefully ground before the parts are assembled. Should the upper edge of the bar project above the surface of the cylindrical body, after the bar has been properly seated in the groove, the exterior surface of the pivot can be ground down to the desired diameter that will enable the pivot to be driven into proper position in the openings 21 of the arm 12. This construction has enabled an accurate article to be produced without resorting to the use of screws, bolts or other auxillary fastenings for securing the parts together.

Having thus described my invention, what I claim is:—

1. A scale pivot comprising a cylindrical body portion having a substantially rectangular groove extending longitudinally thereof and a knife-edged bar having parallel side faces for frictionally engaging the side walls of said groove, said knife edge resting on the bottom wall of said groove and being spaced from the side wall thereof.

2. A scale pivot comprising a cylindrical body portion having a substantially rectangular groove extending longitudinally thereof and a knife-edged bar having parallel side faces for frictionally engaging the side walls of said groove, said knife edge resting on the bottom wall of said groove.

In testimony whereof I hereunto sign my name.

ALFRED BOUSFIELD.
